UNITED STATES PATENT OFFICE.

JOSEPH F. MONTINE, OF NEVINVILLE, IOWA.

COLLECTION AND DELIVERY APPARATUS.

1,171,799.

Specification of Letters Patent.

Patented Feb. 15, 1916.

Application filed July 10, 1915. Serial No. 39,153.

To all whom it may concern:

Be it known that I, JOSEPH F. MONTINE, a citizen of the United States, residing at Nevinville, in the county of Adams and State of Iowa, have invented certain new and useful Improvements in Collection and Delivery Apparatus, of which the following is a specification.

This invention relates to apparatus for collecting and delivering mail, parcels, etc., along a route, the same comprising an elevated track on which is mounted a car which carries the mail matter, etc., to be delivered, and which also picks up the same at the stations, the delivery and collection being automatically effected.

An apparatus of the kind stated is disclosed in my Patents, No. 1,122,785, dated December 29, 1914, and No. 1,132,863, dated March 23, 1915, and the present invention is an improvement thereon, the same relating more particularly to the propelling means of the car, the latter being carried by a truck mounted on the elevated track and driven by an electric motor.

The invention has for its object to provide a novel and improved means for preventing the motor truck from jumping the track, and also to level the truck if it should start to rise from the track, and, furthermore, to provide a novel and improved support for the current collector, whereby the same is kept in proper position with respect to the trolley wire at all times and under all conditions of the track and the trolley wire.

The herein stated objects are attained by means of a combination and arrangement of parts to be hereinafter described and claimed, and in order that the same may be better understood, reference is had to the accompanying drawings in which—

Figure 1 is a side elevation of the truck, partly in section; Fig. 2 is a vertical section on the line 2—2 of Fig. 1; Figs. 3 and 4 are sectional details on the lines 3—3 and 4—4, respectively, of Fig. 1; Fig. 5 is a horizontal section on the line 5—5 of Fig. 2; Fig. 6 is a side elevation showing a modification; Fig. 7 is a horizontal section on the line 7—7 of Fig. 6; Fig. 8 is a cross-section on the line 8—8 of Fig. 7, and Fig. 9 is an elevation of a detail.

Referring specifically to the drawings, 55 10 denotes a fragment of a suitable car or receiver designed to hold the mail matter,

parcels or other articles to be collected and distributed along the route. The car is suspended from an elevated track in the form of a cable 11 supported by bracket arms 12 mounted on poles 13 positioned at suitable intervals along the route. On the cable 11 is mounted a truck for propelling the car, the latter being carried by and suspended from the truck. One or more propelling trucks are provided according to the size of the car. Ordinarily two trucks are sufficient, one for each end of the car. The trucks are propelled by electric motors suitably geared to the wheels thereof, and obtaining current from an overhead conductor 14 strung above the cable or track 11, and supported by bracket arms 15 carried by the poles 13.

At the outer end of the bracket arm 12 is an upstanding part 16 in the top of which is a groove, which forms a seat for the cable 11, and the latter is held in this seat by a clip 17 welded or otherwise secured to the side of the part 16 and having a top bend 80 across the cable. The part 16 is of sufficient length to provide a substantial support for the cable and its ends are beveled, as indicated at 18, to facilitate the passage of certain guards to be presently described. 85 The conductor 14 is supported in the same manner as the cable 11, the seat being shown at 19 and the clip at 20, the seat also having beveled ends 21.

The truck comprises a base or platform 22 on which the electric motors 23 are mounted, said motors being suitably geared to the wheels 24 of the truck for propelling the same along the cable 11. The truck wheels have grooved peripheries and they 95 are so positioned that the base is spaced a sufficient distance above the cable to clear the latter. At the ends of the base are depending, forked guards 25, which straddle the cable, and are integral with the base, 100 or separate and made fast thereon. The guards also have sufficient spread to clear the parts 16 and 17. A suitable housing 26, carried by the base, incloses the motors 23. Midway between its front and rear ends, 105 the truck carries a hanger comprising a hub 27 and stems 28 and 29 extending from the latter. These stems are offset laterally relative to each other and one extends upward and the other downward. The bottom stem 110 28 carries a depending stem 30 which supports the car, the connection being like that

shown in the hereinbefore noted Patent No. 1,122,785, dated December 29, 1914.

In the truck base or platform 22 is an opening 31 to accommodate the hanger hub 27, and a pivot pin or bolt 32 passing through the hub and the base connects the truck pivotally to the hanger, the pivotal axis being transversely of the truck. Beneath the truck base 22, the hanger stem 28 carries a bowed spring 33 extending forwardly and rearwardly of the stem and having its free ends pressing against the bottom of the truck base, on opposite sides of the pivot 32 of the hanger. This spring is located to one side of the cable 11 to clear the same, and its function is to hold the truck level if it should rise from the cable 11. Beneath the spring 33, the hanger stem 28 carries a pivoted arm 34 extending forwardly and rearwardly of said stem and equipped with guard rollers 35 at its ends. These guard rollers are directly beneath the cable 11 and adjacent to the guards 25 of the truck base 22. The arm is pivoted to the stem 28 at 36, and beneath the arm the stem carries a bowed spring 37 the free ends of which press against the under side of the arm 34, on opposite sides of its pivot 36. The rollers 35 prevent the truck from jumping the cable 11, and the spring 33, as already described, keeps the truck level and holds both wheels 24 on the cable. Without the spring 33, the truck might tip or have one wheel on the cable and the other wheel 35 in the air, which would leave an opening for this end to slip off the cable if a bad place on the cable were encountered. The spring 37 holds the arm 34 level so that the rollers are on the same level beneath the cable. By pivoting the supporting arm 34 of the rollers, the latter are enabled to clear the cable support 16, the beveled ends 18 of the latter being in the path of the rollers. Thus when the forward roller strikes the rear bevel 18, the end of the arm carrying this roller tilts downward, and the other or rear end tilts upward so that the roller carried by said rear end of the arm comes close to the cable and the rear guard 25, and thus prevents the truck from jumping the cable. When the rear roller reaches the rear incline, the arm tilts in a direction to bring the front roller close to the cable and the front guard 25, and when said roller 35 clears the cable support, the spring 37 restores the arm to its normal level position so that the rollers will not drag along the cable.

At 38 are shown two current collectors in the form of ordinary trolley wheels mounted for travel on the conductor 14. The trolley wheels are carried by a bracket composed of a horizontal arm 39 having upstanding end portions 40 supporting the trolley wheels in any suitable manner. The bracket

arm 39 is supported midway between its ends by a wooden arm 41, and the latter, in turn, is connected to the upper end of the hanger arm 29, the truck housing 26 having a top opening 42 through which the hanger 70 arm extends. The connection between the arms 39 and 41 is made with a ball-and-socket joint 43, and a similar connection is made between the arm 41 and the stem 29. The trolley wheel supporting members 40 75 carry pivoted guard arms 44 held level by bowed springs 45. These guard arms are located beneath the conductor 14 and their ends are located in advance of and to the rear of the trolley wheels 38. The ends of 80 the arms are curved so that they may glide along the conductor if they strike the same. If the trolley wheels should jump the conductor, the guard arms 44 strike the latter, they being spaced from the conductor such 85 a distance that the trolley wheels cannot rise high enough to let the conductor out of the peripheral groove of the wheels. The ball-and-socket joints 43 and 44 allow the trolley wheels to readily follow curves in 90 the conductor, and they also give the wheels enough side play to follow irregularities in the conductor. The wheels will also follow the conductor if the latter is not perfectly level, and the spacing between the same and 95 the cable 11 varies. As the trolley-wheel supporting-bracket is carried by the stem 29, and the latter is kept upright by the weight of the car 10, the tilting of the truck 100 does not disturb the position of the trolley wheels.

As in the hereinbefore noted Patent No. 1122785, a speed controller for the motors 23 is provided, the same being actuated by a star wheel 46 located on one side of the truck in the path of a trip 47 carried by a bracket arm 48 supported by the pole 13. On the bracket arm 48 is a plate 49 to which the trip is pivoted as indicated at 50. The trip is an arm having at its outer, free end 110 an inwardly extending branch 51 passing slidably through an opening 52 in the plate 49. A spring 53 associated with the branch 51 holds the latter normally advanced, and standing straight out from the plate 49, the arm 47 being inclined. Thus, when the star wheel 46 strikes the arm 47 the latter swings back out of the way as shown dotted in Fig. 5, and no motion is given the star wheel. However, when the star wheel strikes the branch 51 the trip device does not swing back and the star wheel is actuated. This trip structure makes it possible to have one set of trips for one way and another set for the other way when sending cars both ways 125 on the same line. The outer end of the branch 51 carries a deflector plate 54 to properly place the arms of the star wheel in position to intercept the trip so that the star wheel will always be turned far enough 130

to actuate the motor controller. The trip devices will be located along the line whenever needed.

Figs. 6 to 9 show a modified structure designed to permit the guard rollers 35 to pass cable supports which are longer than the distance between the rollers. The structure hereinbefore described does not allow the rollers to pass over such long cable supports. To obviate this difficulty, the rollers of the modified structure are carried by an arm which is in two sections, indicated at 55 and 56, respectively. These sections are pivotally connected at their inner ends and their outer ends carry the respective rollers. The section 55 is pivoted on a pin 57 carried by the stem 28. The pivotal or hinge connection between the sections is made by a pin or bolt 58. The inner end of the section 55 is forked, as indicated at 59, and the corresponding end of the section 56 fits between the fork branches, the pivot pin 58 passing through these lapping parts. In the inner end of the section 56 is an arcuate slot 60 having for its center the pivotal axis 58 of the sections. The fork branches 59 carry a fixed pin 61 which passes through the slot 60. One of the fork branches also carries a sliding latch pin or bolt 62, positioned to enter the slot 60. The fork branch which carries the latch 62 has a lug 63 to which is pivoted one end of a lever 64 and having at its opposite free end a lateral bend 65 which passes loosely through an aperture 66 in the section 55 and carries at its outer end a roller 67. The lever 64 is connected to the latch 62 by a link 68, and a spring 69, connected to the lever, pulls the same toward the fork 59 to hold the latch seated in the slot 60. On the bracket arm 12 is mounted a track for the roller, the same comprising a plate having an oblique end 70 which is in the path of the roller 67. When the roller strikes this end of the plate, the lever 64 is swung in a direction to withdraw the latch 62 from the slot 60. The latch is therefore obstacle-controlled. The arm sections 55 and 56 are then unlocked, and they are free to tilt downward to the extent of the length of the slot 60. When the sections are locked together, the latch 62 is at one end of the slot 60 and the pin 61 is at the other end of the slot. When the sections are unlocked the pin 61 stops the swing thereof upon reaching the end of the slot opposite the end it normally occupies. When the sections 55 and 56 are unlocked as described, the section 56 drops down as shown dotted in Fig. 6 to allow its roller 35 to clear the rear end of the long cable support 16, the front roller 35 not yet having cleared the support. As soon as the rear roller clears the cable support, the leveling spring 37 swings the sections into alignment again, and the spring 69 operates the lever 64 to advance the latch

62 and insert the same back into the slot 60 to lock the sections, the roller 67 having in the meantime slipped off the plate 70, the length of the latter being proportionate to the length of the cable support 16.

70

I claim:

1. The combination of an elevated track, a motor truck mounted on said track, a car suspended from the truck, a hanger supporting the car, a pivotal connection between the hanger and the truck, a pivoted arm carried by the hanger and extending forwardly and rearwardly therefrom, guard rollers carried by the outer ends of the arm, said rollers being located beneath the track 80 in proximity thereto, and a leveling spring for the arm.

2. The combination of an elevated track, a motor truck mounted on said track, a car suspended from the truck, a hanger supporting the car, a pivotal connection between the hanger and the truck, a pivoted arm carried by the hanger and extending forwardly and rearwardly therefrom, guard rollers carried by the outer ends of the arm, 90 said rollers being located beneath the track in proximity thereto, and to the ends of the truck, the truck ends having front and rear guards straddling the track, and a leveling spring for the arm.

95

3. The combination of an elevated track, a motor truck mounted on said track, a car suspended from the truck, a hanger supporting the car, a pivotal connection between the hanger and the truck, a pivoted arm carried by the hanger and extending forwardly and rearwardly therefrom, guard rollers carried by the outer ends of the arm, said rollers being located beneath the track in proximity thereto, a leveling spring for the 100 arm, an upstanding stem carried by the hanger, a current collector, a bracket supporting the collector, an arm supporting the bracket, said arm being carried by the aforesaid stem, and pivotal connections between 105 the arm and the bracket, and between the arm and the stem.

100

4. The combination of an elevated track, a motor truck mounted on said track, a car suspended from the truck, a hanger supporting the car, a pivotal connection between the hanger and the truck, a pivoted arm carried by the hanger and extending forwardly and rearwardly therefrom, guard rollers carried by the outer ends of the arm, 110 said rollers being located beneath the track in proximity thereto, a leveling spring for the arm, an upstanding stem carried by the hanger, a current collector, a bracket supporting the collector, an arm supporting the bracket, said arm being carried by the aforesaid stem, and universal joint connections between the arm and the bracket, and between the arm and the stem.

115

120

125

5. The combination of an elevated track,

130

5 a motor truck mounted on said track, a car suspended from the truck, a hanger supporting the car, a pivotal connection between the hanger and the truck, guard rollers located beneath the track in proximity thereto, 10 a tilting support for the rollers carried by the hanger, and leveling means for the support.

6. The combination of an elevated track, 10 a motor truck mounted on said track, a car suspended from the truck, a hanger supporting the car, a pivotal connection between the hanger and the truck, guard rollers located beneath the truck in proximity thereto and 15 to the ends of the truck, the truck ends having front and rear guards straddling the track, a tilting support for the rollers carried by the hanger, and leveling means for the support.

20 7. The combination of an elevated track, a motor truck mounted on said track, a car suspended from the truck, a hanger supporting the car, a pivotal connection between the hanger and the truck, guard rollers located 25 beneath the track in proximity thereto, a tilting support for the rollers carried by the hanger, leveling means for the support, an upstanding stem carried by the hanger, a current collector, a bracket supporting the 30 collector, an arm supporting the bracket, said arm being carried by the aforesaid stem, and pivotal connections between the arm and the bracket, and between the arm and the stem.

35 8. The combination of an elevated track, a motor truck mounted on said track, a car suspended from the truck, a hanger supporting the car, a pivotal connection between the hanger and the truck, and a spring carried 40 by the hanger and engageable with the bottom of the truck in front of and to the rear of the hanger.

45 9. The combination of an elevated track, a motor truck mounted on said track, a hanger carried by the truck, a car carried by the hanger, a pivoted arm carried by the hanger and extending forwardly and rearwardly therefrom, guard rollers carried by the outer ends of the arm, said rollers being 50 located beneath the track in proximity thereto, and a leveling spring for the arm.

55 10. The combination of an elevated track, a motor truck mounted on said track, a car carried by the truck, a car carried by the hanger, a pivoted arm carried by the hanger and extending forwardly and rearwardly therefrom, guard rollers carried by the outer ends of the arm, said rollers being located beneath the track in proximity 60 thereto, and to the ends of the truck, the truck ends having front and rear guards straddling the track, and a leveling spring for the arm.

65 11. The combination of an elevated track, a motor truck mounted on said track, a

hanger carried by the truck, a car carried by the hanger, a pivoted arm carried by the hanger and extending forwardly and rearwardly therefrom, guard rollers carried by the outer ends of the arm, said rollers being 70 located beneath the track in proximity thereto, a leveling spring for the arm, an upstanding stem carried by the hanger, a current collector, a bracket supporting the collector, an arm supporting the bracket, 75 said arm being carried by the aforesaid stem, and pivotal connections between the arm and the bracket, and between the arm and the stem.

80 12. The combination of an elevated track, a motor truck mounted on said track, a hanger carried by the truck, a car carried by the hanger, guard rollers located beneath the track in proximity thereto, a tilting support for the rollers carried by the hanger, 85 and leveling means for the support.

90 13. The combination of an elevated track, a motor truck mounted on said track, a hanger carried by the truck, a car carried by the hanger, guard rollers located beneath the track in proximity thereto and to the ends of the truck, the truck ends having front and rear guards straddling the track, a tilting support for the rollers carried by the hanger, and leveling means for the 95 support.

100 14. The combination of an elevated track, a motor truck mounted on said track, a hanger carried by the truck, a car carried by the hanger, a pivoted arm carried by the hanger and extending forwardly and rearwardly therefrom, guard rollers carried by the outer ends of the arm, said rollers being located beneath the track in proximity thereto, a leveling spring for the arm, an upstanding stem carried by the hanger, a current collector, a bracket supporting the collector, an arm supporting the bracket, said arm being carried by the aforesaid stem, and universal joint connections between the 110 arm and the bracket, and between the arm and the stem.

115 15. The combination of an elevated track, a motor truck mounted on said track, a hanger carried by the truck, a car carried by the hanger, guard rollers located beneath the track in proximity thereto, a tilting support for the rollers carried by the hanger, said support comprising pivotally connected sections, a latch for locking the 120 sections together, a latch operating means, and an obstacle in the path of the operating means for actuating the same.

125 16. The combination of an elevated track, a motor truck mounted on said track, a hanger carried by the truck, a car carried by the hanger, guard rollers located beneath the track in proximity thereto, a tilting support for the rollers carried by the hanger, 130 said support comprising pivotally connected

sections, a latch for locking the sections together, a latch operating means, an obstacle in the path of the operating means for actuating the same, and means for limiting the 5 swing of the sections when unlocked.

17. The combination of an elevated track, a motor truck mounted on said track, a hanger carried by the truck, a car carried by the hanger, guard rollers located beneath 10 the track in proximity thereto, a tilting support for the rollers carried by the hanger, said support comprising pivotally connected sections, a latch for locking the sections together, a lever operatively connected to the 15 latch, and having a laterally extending portion, and an obstacle in the path of said laterally extending portion of the lever for swinging the lever to withdraw the latch.
18. The combination of an elevated track, a motor truck mounted on said track, a hanger carried by the truck, a car carried by the hanger, guard rollers located beneath 20 the track in proximity thereto, a tilting support for the rollers carried by the hanger, said support comprising pivotally connected sections, a latch for locking the sections together, and means for breaking the support 25 at the joint between the sections thereof.

19. The combination of an elevated track, a motor truck mounted on said track, a hanger carried by the truck, a car carried by the hanger, guard rollers located beneath 30 the track in proximity thereto, a tilting support for the rollers carried by the hanger, said support comprising pivotally connected 35 sections, a latch for locking the sections together, and means for breaking the support at the joint between the sections thereof at predetermined times.

20. The combination of an elevated track, 40 a motor truck mounted on said track, a hanger carried by the truck, a car carried by the hanger, guard rollers located beneath the track in proximity thereto, a tilting support for the rollers carried by the hanger, 45 said support comprising pivotally connected sections, a latch for locking the sections together, and obstacle-controlled means for breaking the support at the joint between 50 the sections thereof.

In testimony whereof I affix my signature in presence of two witnesses.

JOSEPH F. MONTINE.
